TOOL FOR THE INSERTION OF STUDS

Jack M. Bagoon, East Orange, N. J.

Application March 18, 1948, Serial No. 15,689

2 Claims. (Cl. 81—53)

1

This invention relates to tools and more particularly to tools adapted for the insertion of a stud in the attaching end of a leg for an article of furniture such as a bed box spring.

The object of the instant invention is the provision of a simple and effective tool for the insertion of a stud in a member adapted in turn to be attached by the stud to a second member.

A further object is to provide a means for attaching one member to another that is both durable and quickly accomplished.

Other objects of the instant invention will become apparent in the course of the following specification.

In the accomplishment of these objectives, the tool is designed for attachment to a drill press or the like. In the base of the tool is a jaw member which releasably retains one end of a stud while turning the opposite end into a member intended for attachment to a second member by the end of the stud released from the jaw member.

The invention will appear more clearly from the following detailed description when taken in connection with the accompanying drawing showing by way of example a preferred embodiment of the inventive idea.

In the drawing:

Figure 1 is a top view of the tool constructed in accordance with the principles of this invention.

Figure 2 is a sectional view along the line 2—2 of Figure 1 and showing below the tool the means designed to hold the member into which the stud is being turned for the ultimate attachment of said member to a second member (not shown).

Figure 3 is a sectional view along the line 3—3 of Figure 2.

Figure 4 is a sectional view along the line 4—4 of Figure 2.

Referring now in greater detail to the drawings in which like reference numerals indicate like parts, reference numeral 11 indicates the stud, 12 the member into which the stud is being inserted, 13 the vise-like block for holding the member while the stud is being turned therein, and 14 a portion of a drill press to which the tool is attached and by which it is actuated.

The tool is formed of the driver 31, the driven member 16, the housing 17, the opposed jaw members 28 and 28a, and the bottom supporting member 18.

The driver 31 is formed at the top in a suitable manner for attachment to a drill press and at the base with the collar 19a. Of course, other

2

means than a drill press for imparting angular velocity to the tool could be designed. In the base of the collar 19a of the driver 31 is the keyway 19 for insertion of the subsequently described key 20 (Figs. 2 and 3) of the driven member 16.

The driven member 16 is substantially a hollow cylindrical member with closed top on which the key 20 is disposed for fitting into the above-mentioned keyway 19 of the driver 31. Toward the top of the driven member 16 (Fig. 2) is the recess 22 extending around the outside surface portion and into which one or more set screws 22a through the housing 17, later described, are partially inserted. At the base of the driven member 16 is the locking taper 27 in opposed relationship. The opposed ends of the driven member 16 and locking taper 27 are grooved for insertion of the ball bearings 29. The locking taper 27 is maintained in the opposed position by the locking ring 27a which is secured to the driven member 16 by one or more suitable fasteners 24 inserted in registering apertures of the respective members. In the base of the locking ring 27a is an aperture for insertion of the jaw members 28 and 28a.

The jaw member is formed of the two opposed members 28 and 28a designed to be fitted upwardly through the bottom of the driven member 16. At the base, the opposed surface portions of the members 28 and 28a are threaded for the insertion of the stud 11 which is inserted through aligned apertures in the bases of the locking ring 27a and bottom supporting member 18, subsequently described. The outside surface portions of the opposed jaw members 28 and 28a at the base are tapered to co-act with an inside tapered surface portion of the locking taper 27 so that as the jaw members are pushed upwardly into the driven member 16 the opposed surface portions of the jaw members tend to approach each other and to hold a member inserted therebetween, such as the stud 11, with a substantial grip. Near the center of the opposed jaw members 28 and 28a are the opposed recesses 25a and 25b into which the pin 25 is inserted and which serves as a pivotal means for the movement of the upper and lower portions of jaw members 28 and 28a toward and away from each other. An aperture through the pin 25 supports the screw 24, inserted vertically along the vertical center line of the jaw members 28 and 28a, and threaded at the base for attachment to the member 32 as shown in Figure 2. The member 32 is, in turn, inserted in co-acting recesses in the opposed

jaw members, and aids in maintaining the same separated at the base when out of the driven member 16. The coiled spring member 26 maintains the screw 24 in position and may be adjusted by a screw driver through the opening 15 in the top of driven member 16 as shown in Figure 2. At the top of each of the opposed jaw members 28 and 28a are the recesses 23 and 23a. Into the recess 23a is inserted the ball bearing 23b and into the recess 23, the ball bearing 23c, the ball bearings 23b and 23c being held in apertures formed in the walls of the driven member 16 and providing anti-friction surfaces. Similar recesses and ball bearings are disposed at the base of the opposed jaw members 28 and 28a as shown in Figure 2. The width of the recesses into which the ball bearings are disposed as shown as well as the width of the recess 22 at the top is sufficient to permit the necessary vertical movement of the jaw members 28 and 28a in and out of the base of the driven member 16 as later shown.

Concentric with the driven member 16 and around the outside thereof is the housing 17 removably attached to the collar 19a of the driver 31 by the cap 21 which is supported by the upper edge of the collar 19a and then threaded over the upper end of the housing 17 while being held in place by the locking ring 30. Both the cap 21 and the locking ring 30 are adjustable by a spanner wrench or the like.

At the base of the tool 10 is the bottom supporting member 18 designed to be threaded on the base of the housing 17 and held securely in place by the locking ring 33 as shown in Figure 2. In the base of the bottom supporting member 18 is an aperture which registers with the vertical center line of the jaw members 28 and 28a and is designed for the insertion of the stud 11 there-through.

Below the tool is, for example, a leg 12 for any piece of furniture and held from rotating by being inserted in a co-acting aperture in the vise-like block 13. The vise-like block 13 is secured to any suitable support by the screw 34 or the like. Of course, other methods for maintaining the leg 12 non-rotatable could be designed.

The operation is as follows: The top of the leg 12 is inserted in a co-acting aperture in the vise-like block 13. The tool is inserted in the drill press 14, the vertical center lines of the drill press, tool, and leg being substantially aligned. The stud 11, preferably of hard metal, is then inserted through the base of the bottom supporting member 18 between the jaw members 28 and 28a forcing them upwardly into the driven member 16 and thereby maintaining a tight grip on the stud 11 by virtue of the tapered surfaces of said jaw members co-acting with the tapered surface of the locking taper 27. Rotary motion is then imparted to the tool which turns the stud 11 into the leg 12 either by permitting the leg 12 to travel upwardly while being maintained non-rotatable or by permitting the tool to travel downwardly until the opposed surfaces are in contact. When in contact, the housing 17 and bottom supporting member 18 will tend to cease rotating. Thereafter, the driven member 16 and jaw members 28 and 28a will continue to rotate and move downwardly until the set screw 22a reaches the top of the recess 22 whereupon the driven member 16 will cease to move downwardly but the jaw members 28 and 28a will continue to rotate and move downwardly until the downward motion forces the members 28 and 28a out of contact

with the locking taper 27 automatically releasing the stud 11 and permitting the member 32 to move downwardly by action of the spring member 26 thereby maintaining the jaw members 28 and 28a separated.

It is apparent that the specific example shown above has been given by way of illustration and not by way of limitation and that the structures above described are subject to wide variation and modification without departing from the scope or intent of the invention, all of which variations and modifications are to be included within the scope of the present invention.

What is claimed is:

1. A tool for inserting studs comprising a driver, a driven member, a jaw member, a housing, and a bottom supporting member; the driver comprising a cylindrical body portion and adapted at the top for attachment to a drill press, a collar around the base of the cylindrical body portion, and a keyway along the bottom surface portion of the collar; the driven member comprising a substantially hollow cylindrical body portion with closed top, a key on the top surface portion of the closed top of the hollow cylindrical body portion and adapted to be fitted into the keyway of the driver; a locking taper disposed in opposed relationship at the base of the driven member, anti-friction means between the opposed surfaces of said members, and means securing the locking taper at the end of the driven member; the jaw member comprising at least two pivotally opposed members and adapted for insertion through the base of the driven member, the outside surface portions of the jaw members being tapered to co-act with the tapering surface of the locking taper and adapted to bring the bases of the jaw members together when pushed upwardly into the driven member, the opposed surface portions of the jaw members being threaded at the base and adapted for the insertion of the stud; the housing comprising a substantially hollow cylindrical body portion with open top disposed around the collar of the driver and extending downwardly toward the base of the driven member, means securing the housing to the collar of the driver comprising a cap disposed around the collar and threaded over the upper outside surface portion of the housing, and a lock ring disposed around the housing co-acting with the cap in maintaining the same in position; a bottom supporting member removably disposed around the base of the housing and adapted to provide a space between the bottom surface portion of the retaining ring and bottom surface portion of the bottom supporting member, and a locking ring adapted to maintain the bottom supporting member in position on the housing; the tool further comprising vertical adjustment means for the driven member comprising a recess substantially at the top of the driven member and extending around the outside surface portion thereof, a tap through the housing aligned with the recess, and a set screw threaded through the tap partially into the recess, vertically adjustable anti-friction means between the jaw members and driven member, and means maintaining the jaw members releasably separable.
2. A tool for inserting studs according to claim 1 in which the means maintaining the jaw members releasably separable comprises co-acting recesses along the opposed inner surface portions of the jaw members substantially at the center and perpendicular to the longitudinal center line, a pin removably disposed in the recesses and

adapted to pivot the tops and bottoms of the opposed jaw members toward and away from each other, and an aperture through the pin; the said means further comprising co-acting recesses along the opposed inner surface portions of the jaw members substantially at the base, said recesses having a substantially greater diameter at the top than at the bottom, a member removably disposed in the latter recesses and adapted to aid in maintaining the opposed jaw members separated when released from the locking taper, a screw through the aperture in the pin and threaded into said member, and spring tension means maintaining the screw in the desired position.
